UNITED STATES PATENT OFFICE.

JOHN T. ASHTON, OF WILLIMANTIC, CONNECTICUT.

CROW-HICK.

1,125,632.

Specification of Letters Patent.

Patented Jan. 19, 1915.

Application filed July 2, 1914. Serial No. 848,625.

To all whom it may concern:

Be it known that I, JOHN T. ASHTON, citizen of the United States, residing at Willimantic, in the county of Windham and State 5 of Connecticut, have invented certain new and useful Improvements in Crow-Hicks, of which the following is a specification.

My invention relates to an improvement in electrical fixtures known as crow-hicks, 10 and it comprises a crow foot adapted to be secured to any support, and a hickey detachably connected with said crow foot.

In the accompanying drawings: Figure 1 15 is a view in side elevation; Fig. 2 is a perspective view of one of the parts; Fig. 3 is a perspective view of the other; Fig. 4 is a section through the two parts of the fixture when assembled on line 4—4 of Fig. 5; and Fig. 5 is a plan view of the invention.

20 The crow comprises a ring 1 and a center 2 integral with each other, the latter terminating in three feet, 3, 3, 3, having screw holes 4 in each, said feet preferably thicker, say double the thickness of the ring.

25 The hickey comprises a cylindrical portion 5 having three notches 6, 6, 6 therein, of a size and thickness adapted to receive and fit the feet 3, 3, 3 of the crow foot.

30 The spider portion of the hickey preferably comprises a center 7 having an orifice 8 in its center, wherein to receive the stem 9 of the fixture, which stem is held therein by a set screw 10 on the side of this center.

The parts are held together by a screw 11 which passes through a hole 12 in one of the 35 three legs of the spider, and into a threaded hole 13 in the center of the crow foot.

The parts are kept from turning with respect to each other by means of the notches between the feet of the crow foot, and the 40 members are detachably held together by the screw passing through the hickey into the crow foot. In this way a very simple fixture is provided composed of few parts, 45 easily secured together or taken apart. At the same time it affords a practical outlet 50 box for attachment to the wall or other support, and for receiving the fixture to be supported.

I claim:

An electrical fixture comprising a crow 55 foot composed of a center, ring, and legs integral with the ring and of greater thickness than the latter, and a hickey composed of a cylinder and spider, the cylinder having notches to receive the legs, thereby to prevent the crow foot and hickey from turning with respect to each other, and means for securing said parts detachably together.

In testimony whereof I affix my signature 60 in the presence of two witnesses.

JOHN T. ASHTON.
